DUAL SLIDER UNIT

Louis H. Morin, Bronx, N. Y., assignor of one-half to Davis Marinsky, Bronx, N. Y.

Application December 12, 1942, Serial No. 468,759

12 Claims. (Cl. 24—205)

This invention relates to separable fasteners employing stringers coupled and uncoupled by sliders movable along the stringers. More particularly, the invention comprises a dual slider unit having a hollow body with contracted end portions with means for supporting sliders at the contracted end portions of the body for universal movement thereof; and still further in the provision of a unit of this kind having guide channels at opposed sides of the unit for supporting the links of the stringers in a position angularly to the normal engaging position thereof, thereby leaving the separated stringers free intermediate the channels and the spaced sliders. The novel features of the invention will be best understood from the following description when taken together with the accompanying drawing, in which certain embodiments of the invention are disclosed, and in which the separate parts are designated by suitable reference characters in each of the views and in which:

Fig. 1 is a plan view of one form of slider unit made according to my invention diagrammatically illustrating one adaptation and use thereof.

Fig. 2 is a bottom plan view of the unit indicating in dotted lines the approximate outline of the tape and in dot and dash lines, the path of the links of the stringers when uncoupled by the unit.

Fig. 3 is a longitudinal section on the line 3—3 of Fig. 2.

Fig. 4 is a cross section on the line 4—4 of Fig. 2.

Fig. 5 is a section on the line 5—5 of Fig. 3.

Fig. 6 is a view similar to Fig. 2 showing only a part of the construction and showing a modification.

Fig. 7 is a section on the line 7—7 of Fig. 6, indicating the position of the stringer links in the devices; and

Fig. 8 is a section on the line 8—8 of Fig. 6.

In separable fastener stringers of the double action type, such as described in my prior application Ser. No. 444,189, filed May 23, 1942, Patent No. 2,322,537, granted June 22, 1943, there have been uses of two sliders arranged upon a pair of stringers to couple and uncouple the stringers. By reason of the double action properties of the links of the stringers, the sliders will freely couple the stringers in any arrangement of the sliders thereon. The present invention deals with a unit construction, which comprises a body having end portions in connection with which sliders are coupled, so that in moving the unit along the stringers, the sliders will maintain the stringers coupled beyond the limits of the unit, while sepa-

rating the stringers intermediate the spaced sliders.

To give one illustration of an adaptation and use of the invention, the unit is made in the form of a hollow or apertured body to receive, for example the barrel of a gun. In such uses, the gun barrel is movable in an elongated slot or passage and the fastener is employed to maintain the passage closed, except for that part of the passage occupied momentarily by the gun barrel. In some installations of this kind, the slot or opening through which the gun barrel travels is substantially straight or arranged in a substantially flat surface. In other instances, however, the barrel is arranged to move through a turret having varying curvatures and in such instances, the slider unit is arranged upon a contour fastener, as specifically described in my prior application Ser. No. 444,189, filed May 23, 1942, and as diagrammatically illustrated in Fig. 1 of the drawing.

In Fig. 1, 10 and 11 represent the stringers of a separable fastener, wherein the spacing of the links on opposed stringers are such as to give a curved contour to the resulting fastener, as indicated by the curvatures 12, 13. At 14 is shown a slider unit comprising a hollow or apertured body 15, the opening through which is indicated at 16. This opening will be of such contour and dimensions as to receive the article or member to be arranged therein and the walls of the aperture or opening 16 are preferably rounded, as indicated in Fig. 3 of the drawing, in order to compensate for different angular positions that may be assumed by the body 15.

The body 15 has contracted end portions 17, 17', each having on one side surface recesses 18, 18' centrally of which are apertures 19, 19'.

More or less conventional sliders 20, 20' are adapted for mounting in connection with the end portions 17, 17', the sliders comprising the usual channeled bodies formed by spaced walls 21, 22 joined at the wide end by a connecting web 23 and the wall 21 of each slider has spaced outwardly projecting pivot bearings 24, note Fig. 5, with which is pivoted a coupling joint 25 by a pin 26. The coupling joint is in the form of a disc 27, having downwardly projecting apertured lugs 28 adapted to be arranged within the bearings 24 and an upwardly projecting pin 29 recessed to receive a split ring 30 employed to support the sliders against displacement from the contracted ends 17, 17'. It will appear that the pins 29 are free to rotate in the apertures 19, 19'. Thus, this construction provides a universal mounting

of the sliders 20, 20' in connection with the end portions 17, 17'.

The opposed side walls of the body 15 have downwardly or inwardly directed plate portions 31 and the outer portions of said sides have substantially L-shaped flanges 32, which form part of guide channels 33 for guiding the links of the stringers at the wide side portions of the body 15. The other portion of the channels 33 is formed by flanged plates 34 of the general cross sectional contour, seen in Fig. 4; and secured to the plates 31 by screws 35. It will appear that the channels 33 support the links of the stringers in a position angularly to the normal coupling position of the stringers.

It will appear from a consideration of Figs. 2 and 3 of the drawing that there is a wide spacing between the side channels 33 and the wide diverging channel ends of the sliders 20, 20'. This spacing leaves the links of the stringers free between the sliders 20, 20' and the channels 33 and also in spaced relation to the walls 36 of the body 15. This construction is desirable in certain uses of the invention and particularly where the apparatus, in connection with which the closure is employed, is subject to extremely low temperatures, for example, on airplanes or tanks that may be exposed to freezing temperatures. In the event that ice may collect or form on the fastener and around the unit 14, the free mounting of the links of the stringers will enable the unit to be operated and to break up any ice formation which may prevail. In other adaptations and uses of the invention, it will be understood that the body 15 may be made to conform with the line of travel of the spaced stringers between the sliders and the channels 33. However, the free mounting of the stringers as above described is also desirable from the standpoint of minimizing frictional engagement; thus producing a freer operation of the unit along the stringers.

In Figs. 6-8 inclusive is shown a modified structure, wherein the body 37 of the dual slider unit has at its contracted ends flanged sockets 38 for receiving sliders 39. The sliders have spaced bearings 40, through which a pivot pin, such for example as cotter pins 41, is passed for pivotally coupling the sliders in connection with said end portions, the pins passing through apertures 42 in the spaced flanges of the sockets 38. The apertures 43 in the bearings 40 are made sufficiently large so as to provide lateral tilting movement of the sliders 39, the sockets 38 being also sufficiently large to compensate for this movement. It will thus be seen that the sliders 39 will have a universal mounting, within said limits, in connection with the body 37. In the accompanying drawing only one end portion of the body 37 is shown and duplication of the other end is unnecessary.

At the wide side portions of the body 37 are formed channels 44 to receive the links 45 of stringers 46, 47. The channels 44 are formed by angular walls 48 on the body 37 and by L-shaped plates 49 secured to the body 37 by screws 50. The aperture or opening 51 in the body 37 has curved walls, as indicated in Fig. 7, to compensate for movement of the body 37 relatively to a barrel or other member arranged in the aperture 51.

It will be apparent that, in the structure shown in Figs. 6-8 inclusive, the sliders may be said to have horizontal pivots in contrast to what might be termed vertical pivots as disclosed in Figs. 1-5 inclusive.

It will also be apparent that the universal

mounting of the sliders, in connection with the ends of the apertured bodies, compensates for any irregular or curved paths traversed by the unit in the movement of the unit from one end of the stringers to the opposite end thereof.

For purposes of description, the body of the unit may be said to have terminal ends, with which the sliders are coupled. In referring to sliders, it is understood that references are made to substantially conventional sliders of this kind having the diverging channels at the wide end thereof converge to a single channel at the other narrower end of said sliders.

Having fully described my invention, what I claim as new and desire to secure by Letters Patent is:

1. A slider unit for separable fasteners employing stringers, said unit comprising a hollow body having contracted terminal ends, sliders arranged at the contracted ends of said body, and means coupling the sliders to opposite sides of said body and adapted to provide universal movement of the sliders on the hollow body.

2. A slider unit for separable fasteners employing stringers, said unit comprising a hollow body having contracted terminal ends, sliders arranged at the contracted ends of said body, means coupling the sliders for universal movement on said terminal ends, said last named means comprising coupling members pivotally attached to the sliders, and said members having pin portions rotatably mounted in the terminal ends of said body.

3. A slider unit for separable fasteners employing stringers, said unit comprising a hollow body having contracted terminal ends, sliders arranged at the contracted ends of said body, means coupling the sliders for universal movement on said terminal ends, said last named means comprising coupling members pivotally attached to the sliders, said members having pin portions rotatably mounted in the terminal ends of said body, and means retaining said members against displacement from said terminal ends.

4. A slider unit for separable fasteners employing stringers, said unit comprising a hollow body having contracted terminal ends, sliders arranged at the contracted ends of said body, means coupling the sliders to opposite sides of said body and adapted to provide universal movement of the sliders on the hollow body, and means at side portions of said body centrally thereof forming guide channels for the links of stringers movable between spaced sliders on said body.

5. A slider unit for separable fasteners employing stringers having links, said unit comprising a hollow body having contracted terminal ends, sliders arranged at the contracted ends of said body, means coupling the sliders for universal movement on said terminal ends, means at side portions of said body centrally thereof forming guide channels for the links of stringers movable between spaced sliders on said body, said channels supporting the stringers in spaced relationship and beyond the limits of the opening in said body, and said channels also supporting the links of the stringers in a position angularly to the normal coupling position of said links.

6. A dual slider unit for separable fastener stringers, said unit comprising an elongated body means for guiding the links of a pair of stringers in spaced relationship to each other longitudinally of said body, sliders arranged at terminal ends of the body with diverging channels of said sliders directed inwardly, thereby maintaining cou-

pling engagement of the stringers beyond the limits of both ends of said body in the movement of the body longitudinally of the stringers, and means pivoting the sliders to said terminal ends to swing on an axis disposed transversely to the longitudinal plane of said body.

7. A dual slider unit for separable fastener stringers, said unit comprising an elongated body, means for guiding the links of a pair of stringers in spaced relationship to each other longitudinally of said body, sliders arranged at terminal ends of the body with diverging channels of said sliders directed inwardly, thereby maintaining coupling engagement of the stringers beyond the limits of both ends of said body in the movement of the body longitudinally of the stringers, means pivoting the sliders to said terminal ends to swing on an axis disposed transversely to the longitudinal plane of said body, and means comprising perpendicular pins for rotatably mounting the sliders in said terminal ends.

8. A dual slider unit for separable fastener stringers, said unit comprising an elongated body, means for guiding the links of a pair of stringers in spaced relationship to each other longitudinally of said body, sliders arranged at terminal ends of the body with diverging channels of said sliders directed inwardly, thereby maintaining coupling engagement of the stringers beyond the limits of both ends of said body in the movement of the body longitudinally of the stringers, means pivoting the sliders to said terminal ends to swing on an axis disposed transversely to the longitudinal plane of said body, means comprising perpendicular pins for rotatably mounting the sliders in said terminal ends, and the contour of said body intermediate the first named means and said sliders providing free passage of the stringer links between the sliders and said first named means.

9. In a device for use on separable fastener stringers, a pair of sliders movable along the

stringers in spaced relationship to each other, means coupling and spacing said sliders, and means universally coupling the sliders with said first named means at opposite sides thereof.

- 5 10. In a device for use on separable fastener stringers, a pair of sliders movable along the stringers in spaced relationship to each other, means coupling and spacing said sliders, means universally coupling the sliders with said first 10 named means, said first named means comprising a body having a large aperture centrally thereof, and means detachable with respect to opposed sides of said body forming, in conjunction with the body, channels for guiding the links 15 of the stringers.
11. In a device for use on separable fastener stringers having links, a pair of sliders movable along the stringers in spaced relationship to each other, means coupling and spacing said sliders, means universally coupling the sliders with said first 20 named means, said first named means comprising a body having a large aperture centrally thereof, means detachable with respect to opposed sides of said body forming, in conjunction with the body, channels for guiding the links 25 of the stringers, and both sides of said body between the last named means and the sliders being spaced from the stringer links in the movement of said body longitudinally of the stringers.
- 30 12. A dual slider unit movable along fastener stringers having links to couple and uncouple the same, said unit having terminal ends arranged in predetermined spaced relationship to each other, sliders coupled to said terminal ends 35 to provide rocking and swinging movement of the sliders on said body in the movement of the body longitudinally of the stringers, and means on the body intermediate said sliders for supporting the links of the stringers in spaced relationship to each other and in a position angular to 40 the normal coupling position of said links.

LOUIS H. MORIN.
